UNITED STATES PATENT OFFICE.

HENRY P. RICHMOND AND THOMAS E. CARPENTER, OF PROVIDENCE, R. I.

DESIGN FOR A FINGER-RING.

SPECIFICATION forming part of Design No. 12,652, dated January 3, 1882.

Application filed November 10, 1881. Term of patent 14 years.

To all whom it may concern:

Be it known that we, HENRY P. RICHMOND and THOMAS E. CARPENTER, citizens of the United States, residing at Providence, in the county of Providence and State of Rhode Island, have invented and produced a new and original Design for Finger-Rings, of which the following is a specification, reference being had to the accompanying drawings, forming part thereof.

Figure 1 is a plan or face view of our newly-designed ring, and Fig. 2 a sectional view of the same on the line *xy*, Fig. 1, these two views being deemed necessary to fully illustrate our

design.

Heretofore finger-rings of the class known to the art as "flush" or "glove" rings, and to which our new design particularly relates, have been made with one or more stones set in the head of the ring in various forms and colors.

The leading feature of our design consists in having two or more oblong stones of different colors set side by side lengthwise in the head of a ring of gold, each stone being embedded in the head in a setting of its own, so that a portion only of the gold of the head which forms a part of each setting separates them, as in Fig. 1.

C is the head of the ring, which is rectan-

gular in its general contour, having the shank 30 tapering from the side of the head at *f*. In the top or face of the head C are formed side by side two or more rectangular cavities or box-settings, into which are placed lengthwise and secured two or more different-colored oblong stones, *a a a*, separated from each other by the partitions or sides of the settings *b b*. The top surfaces of the stones *a a a* are finished flush with the top or face of the head of the ring, as in Fig. 2. Thus the ring head presents 40 to the eye alternate oblong figures of different-colored stones set lengthwise and separated by partitions of gold.

We claim—

The design for a flush or glove ring herein 45 shown and described, the same consisting of two or more oblong stones, *a a a*, of different colors, embedded side by side lengthwise in the head of a ring of gold and separated from each other by the partitions *b b*, said stones 50 having their top surfaces finished flush with the top face of the head of the ring.
